STEERABLE JET PROPELLER BOAT

Thomas W. Lepkowski, New York, N. Y.

Application May 12, 1948, Serial No. 26,605

1 Claim. (Cl. 115—12)

1

The invention relates to propulsion means for toy boats and similar floating articles, adapted to travel on water, and of the jet type embodying a suitable actuator steam boiler adapted for automatic intake and discharge of water received through a tube or tubes having their outer end or ends submerged in the water during operation of the toy.

The invention has for an object, in toys of this nature, to provide simple and efficient means for effecting the propulsion of the craft, said means being readily adaptable particularly to toy craft, for example, for use as an outboard motor member, and in a manner to allow of variously maneuvering the craft.

A further object of the invention is to provide discharge means from the boiler, which itself embodies novel features, whereby also the steering of the craft is effected.

A still further object of the invention is to locate a heating means for the boiler eccentrically with respect to the under surface of the same; and also to provide heating means, the burner nozzle portion of which may be adjusted relatively to said under surface for control of the speed of the boat.

Another object of the invention is to associate manually actuated ignition means with the burner nozzle.

The invention has for an object, also, propulsion means which do not become an integral part of a hull but may conveniently be located variously on the deck thereof so that the hull need not be constructed of metal.

In the usual form of propulsion means utilized in craft of the aforesaid type and due to the fact that the heat delivered is critical, boiler members as heretofore constructed vibrate irregularly and are likely to flood with water and cause choking and temporary stoppage until enough water has been changed into steam to continue operation, or until the boiler runs dry bringing the operation to an end.

When using fuel such as alcohol in jellified or tablet form, this rapid termination of the boiler operation was not so objectionable since it is not difficult to supplement the fuel. However, when liquid fuel is utilized which permits periods of operation extended from several minutes to half an hour or more, it becomes necessary that the intake of the water be regulated to prevent this flooding, together with a heat control to obviate running dry the boiler.

To this end it is proposed to provide a novel discharge member or members in the nature of

5 a resilient tip or tips, as of rubber, with constricted outlet portion; also, to provide a novel membrane for the boiler element designed to oscillate in varying sections according to the degree of heat applied to the boiler. By this expedient, each time water is drawn into the boiler through a tube, a portion of the resilient discharge tip thereof will be compressed to slow down the intake, thus preventing flooding of the 10 boiler. However, if the usual type of boiler closure membrane were used, the boiler would then run dry even more quickly since the atmospheric pressure affects the whole surface of the membrane which oscillates then as a single unit 15 to force considerable amounts of the water at a time from the boiler.

By constructing the membrane in the manner proposed herein, the latter operates in sections according to the degree of heat supplied so that 20 only as much of the total area is activated to oscillate as required in accordance with the propulsion system. The construction of the diaphragm to this end is such, preferably, that the oscillations spread from the center thereof 25 radially outwardly in widening circles. This diaphragm construction permits, also, of speed regulation through adjustment of the heating means associated with the boiler, the membrane reacting immediately upon any change in the 30 heat conditions, which may be readily adjusted to prevent premature running dry of the boiler.

The effect of the resilient tip of the tube on the discharge of water from the boiler is to create a temporary overpressure of steam to augment the thrust of the jet through contraction of an expanded tip and will thus extend the period of oscillation of the diaphragm. In constricting the end of the resilient tip, the jet pipe as a whole may be materially shortened.

35 40 The nature of the invention, however, will best be understood when described in connection with the accompanying drawings, in which:

Fig. 1 is a side elevation of a hull equipped with the novel actuator and steering means unit.

45 Fig. 2 is a plan view thereof and shows also, in broken lines, the jet or discharge means and boiler adjusted bodily to a different angular position relative to the longitudinal axis of the boat.

Fig. 3 is a stern view of a boat equipped with the novel unit.

Fig. 4 is a fragmentary transverse section of the boiler on an enlarged scale.

50 Figs. 5 and 6 are fragmentary elevations of the tip portion of the jet intake and discharge

means, the dotted line positions generally indicating the shape assumed respectively during discharge and during intake of water.

Fig. 7 is a side elevation illustrating a modification in the boiler and jet intake and discharge means combination, and a cabin element being indicated in dotted lines over the actuator portion.

Fig. 8 is a plan view thereof, and Fig. 9 a stern view.

Fig. 10 is a fragmentary side elevation illustrating the actuator, jet intake and discharge means unit of Figs. 8 and 9 mounted as an outboard motor device.

Fig. 11 is a fragmentary plan view illustrating automatic lighting means associated with the burner of the actuator.

Fig. 12 is a fragmentary view partly in section illustrating means for mounting the fuel supply tank with burner in a manner to adjust the latter toward and away from the boiler.

Referring to the drawings, one embodiment of the invention is indicated in Figs. 1-6, inclusive, this particular form of the invention including multiple jet means connected with an actuator or flash type of boiler common thereto, the arrangement being such that the jet means and boiler, as well as a fuel supplying means for providing heat to the boiler, constitute a single unit. Thus, such unit may be attached conveniently to the deck 10 of a craft, shown in the particular embodiment as a solid hull 11 such as of wood or other buoyant material, the jet means depending from the boiler at the stern of the hull with outlets designed to be submerged in the water in which the craft floats. It is understood, of course, that the unit may be located on the deck otherwise than as shown for various maneuvering of the craft, for example, at the bow to operate the craft backwards, or along the side of the hull for obtaining angular propulsion of the craft.

As indicated, the jet means which comprise three rigid tubular members 12 with tips 13 of resilient material are directly connected to the circular actuator member 14 and eccentrically thereof, being suspended therefrom to move as a unit therewith in steering the craft. The jet means preferably enter the boiler at different levels.

A handle member 15 may be attached to the top of the actuator or boiler member 14 to adjust the same angularly; and the said boiler to this end is mounted to rotate upon a rod 16 which extends upwardly from the supporting plate 17 of the unit. It is preferred to provide about the rod a bushing 18 to afford a bearing for a sleeve 19 integral with the under surface 20 of the boiler 14, there being sufficient friction between said sleeve and rod to retain the jets in the desired adjusted location.

The necessary heat for operating the boiler is provided by a burner nozzle 21 connected with a fuel tank 22 mounted to rock in a plane normal to the deck whereby the degree of heat applied to the under surface 20 of the boiler 14 may be varied in accordance with the position of the nozzle. Thus, brackets 23 extending upwardly from the plate 17 serve to mount the cylindrical fuel tank 22, with filling cap 24 provided at the top of the tank. Tank 22 carries also a rearwardly directed arm 25 designed to engage the free end of an adjustable screw 26 mounted in a further bracket 27 extending upwardly from the plate, the said screw being provided with a manipulating head 28 whereby, in accordance with the

adjustment of said screw, the fuel tank will be rocked to vary the position of burner nozzle 21 with respect to the under surface 20 of the boiler.

The boiler itself is in the form of a pan-shaped casing, Fig. 4, closed at the top by a flexible circular diaphragm 30 held to the casing around its circumference, said diaphragm, however, being provided with concentric circular scorings or weakening incisions 31 on its outer surface and similar scorings 32 on the inner surface of said diaphragm, the latter scorings being positioned intermediate the former. This affords a diaphragm which will bend uniformly, generally in all directions, to oscillate in sections, said oscillations starting from the center of the diaphragm, for example, and spreading in widening circles in accordance with the intensity of heat applied to the boiler, the diaphragm reacting immediately upon any change in heat conditions. Thus, with only a small amount of heat applied, only the central portion will vibrate and not until the maximum heat is applied will the oscillations continue to the circumference of the diaphragm. Such a diaphragm, due to its enhanced amplitude, greatly increases the efficiency of operation and will produce a deeper sound effect of discharge.

By providing for a multiplicity of the jet pipes comprising the elements 12-13, greater flexibility is imparted to the system permitting of greater constriction of the outlets of the tips 13, which in turn will tend to increase the speed developed by the unit. Such constriction, indicated at 33 at the discharge end of the flexible tip portion 13, will serve to check the intake of water through the jet pipe through contraction as a result of compression of the portion 13, as indicated in the dotted line position, Fig. 6, so that flooding of the boiler is prevented; and the discharge from the boiler will be retarded initially to expand the portion 13 as indicated in the dotted position, Fig. 5, and enable temporarily the creation of excess pressure of steam in the boiler to accelerate with the resiliency action of the tip the discharge of steam and water, as well as prolong the period and smooth out the shock of discharge from a tip.

I have discovered, also, that for best efficiency of the system a certain relation must exist between the area of the diaphragm 30, number of the jet means, and the area of the exhaust orifices of a tip 13. A very satisfactory result is attained with an area ratio of ten to one between membrane and orifice. It is desirable for best results that the number of these jet means be increased with increase of diaphragm area so as to maintain as small as possible the exhaust orifices so essential in developing speed. By increasing the number of tubes, their length may be materially decreased; both of which increases the frequency of the diaphragm oscillations and the efficiency of the system.

Referring to Figs. 7-9, inclusive, a modification is indicated in the location of the boiler member 35 and its mounting. In this particular embodiment, the jet tube 36 is indicated as passing through the hull 37, the boiler being supported on the plate 38 through a tube 39 which also extends partly into the hull to receive the inner end of the jet tube 36. The latter is provided over its exterior with an integral ring portion 40 as a stop for engaging the outer end of tube 39 into which the jet tube 36 telescopes to bring its inner end substantially flush with the bottom of boiler 35. The fit between tube 39 and jet tube 36 is a frictional one permitting the former to rotate in a

horizontal plane to change the direction of discharge from the tip 41 to suit the desired steering of the craft. It will be noted also that tube 39 is mounted eccentrically with respect to the boiler 35, thus permitting better distribution of heat from the burner nozzle 42 communicating with a fuel supply tank 43—all carried by a plate 38. A housing or simulation of a cabin 44 may be provided over the entire power mechanism, as indicated in dotted lines, Fig. 7, and full lines, Figs. 8 and 9.

Also, as indicated in Fig. 10, the entire unit may be utilized as an outboard propulsion means at the stern of the craft by merely securing the plate 38 to the deck with a portion thereof overhanging the stern. In all the embodiments, the arrangement is such that the fuel supply tank with burner nozzle may be located ahead of the boiler, in the direction of travel, so that the maximum amount of heat developed is applicable to the boiler.

The heating means, being of a nature to utilize liquid fuel contained in a tank 50, Fig. 11, feeding a wick member 51, lends itself to the use of automatic ignition means therefor such as the pyrophoric alloy type. As indicated, this may comprise a sparking wheel 52 engaging the alloy material in proximity to the wick 51, said wheel 52 being engaged by a rack member 53 conveniently actuated by a spring cable combination having the manually operated button 54 and digital grip 55, as is well understood.

I claim:

The combination with a power-propelled boat;

of a propulsion unit therefor comprising a flash-type boiler for converting water into steam and provided with an outlet, said boiler being adapted for horizontal disposition over the boat deck, a burner located on the deck including an element with outlet for directing a flame beneath the boiler, a sleeve extending upwardly of the deck substantially in the steering axis of the boat with its upper end supporting the boiler at its outlet for communication with the interior thereof, immersible jet pipe means extending at one end into the sleeve for complete rotation therein as a unit about an axis normal to the boat deck, the immersed portion of the jet pipe means serving also as a rudder in steering the boat and whereby the boat may be displaced laterally as well as steered in all directions.

THOMAS W. LEPKOWSKI.
